SAW

Raymond C. Dreier, Chicago, Ill., assignor to Dreier
Brothers, Inc., Chicago, Ill., a corporation of Illinois

Application January 18, 1954, Serial No. 28,545

Term of patent 14 years

(Cl. D93—4)

To all whom it may concern:

Be it known that I, Raymond C. Dreier, a citizen of the United States, residing at Chicago, in the county of Cook and State of Illinois, have invented a new, original, and ornamental Design for a Saw, of which the following is a specification, reference being had to the accompanying drawing, forming part thereof, wherein:

Fig. 1 is a plan view of a saw embodying my new design;

Fig. 2 is a top view thereof;

Fig. 3 is an end view on an enlarged scale, of the handle as seen from the left of Fig. 1;

Fig. 4 is a sectional view, also on an enlarged scale, taken through the frame substantially along the line 4—4 in Fig. 1;

Fig. 5 is an enlarged sectional view taken vertically

through the center of the handle; and

Fig. 6 is a transverse sectional view taken along the line 6—6 in Fig. 5.

The dominant feature of my design resides in the portion shown in full lines.

I claim:

The ornamental design for a saw, substantially as shown and described.
